United States Patent Office.

HOSEA WILLARD, OF VERGENNES, VERMONT.

Letters Patent No. 65,979, dated June 18, 1867.

IMPROVED CLOTHES-DRYER.

The Schedule referred to in these Letters Patent and making part of the same.

TO ALL WHOM IT MAY CONCERN:

Be it known that I, HOSEA WILLARD, of Vergennes in the county of Addison, and State of Vermont, have invented a new and improved Clothes-Bar; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention relates to a new and improved clothes-bar for holding clothes for drying, and is an improvement on a device for a similar purpose for which Letters Patent were granted to me bearing date February 18, 1862.

The original invention has its bars applied to the bracket in such a manner that they can, when not desired for use, be folded upward only, and the within-described invention consists in applying the bars to the bracket in such a manner that they can be folded either upward or downward, as desired, and which is an improvement from the fact that in many instances the bars when folded upward are very inconvenient to reach, and, in that case, may be folded or turned downward. In the accompanying sheet of drawings—

Figure 1 is a plan or top view of my invention.

Figure 2, a vertical section of the same, taken in the line $\# x$, fig. 1.

Similar letters of reference indicate like parts.

A represents a bracket, which may be of the same form and construction as that shown and described in my original Letters Patent, but instead of being secured permanently to a wall or fixture is provided with a dove-tail rib, α , to fit into a corresponding socket, b , attached to the wall or other fixture, it being designed to have a plurality of sockets accompany each bracket, so that the former may be secured in different places where the device may be required to be used, and the latter adjusted in any of these places. B represents the bars, which are designed to be of wood, the bracket being of cast iron. These bars, as hitherto, are supported by stirrups c cast with the bracket, each bar having an oblong staple, d , in its under side, through which pins e at the feet or bottom of the stirrups pass. The stirrups extend down obliquely or in an inclined direction from the bracket to admit of the bars being folded upward or downward, upward as shown in red, and downward as shown in blue in fig. 2, and the bars, when required for use, are held in a horizontal position by shoving their rear ends underneath the edge of the brackets. The oblong form of the staples d admits of this longitudinal adjustment of the bars B, and it is an important feature, as it enables the bars to be adjusted in a pendent position. In the original device the staples do not allow the bars to be adjusted longitudinally in the stirrups, and hence the former can only be folded upward, as shown in red. The oblong staples, it will be seen, admit of the bars B being drawn out so that their inner ends will be free from the edge of the bracket, and the bars may then be turned down.

Having thus described my invention, I claim as new, and desire to secure by Letters Patent—

The securing of the clothes-bars B in the stirrups c of the bracket by means of oblong staples d , or their equivalents, to admit of the longitudinal adjustment of the bars in the stirrups, substantially as and for the purpose specified.

HOSEA WILLARD.
